UNITED STATES PATENT OFFICE

JOSEPH G. FISHER, OF NEWARK, NEW JERSEY

DESIGN FOR A CRYSTAL PENDANT

Application filed May 1, 1930. Serial No. 35,465. Term of patent 3½ years.

To all whom it may concern:

Be it known that I, JOSEPH G. FISHER, a citizen of the United States, residing in the city of Newark, in the county of Essex and State of New Jersey, have invented a new, original, and ornamental Design for Crystal Pendant, of which the following is a specification, reference being had to the accompanying drawing, forming a part thereof.

In the drawing:

The figure represents a perspective view of a crystal pendant embodying my new design.

I claim:

The ornamental design for a crystal pendant, as shown.

JOSEPH G. FISHER.
